CLAIM

The ornamental design for a combined golf divot repair tool, cleat tightener ball marker, dirt scraper and club holder, as shown.

DESCRIPTION

FIG. 1 is a perspective view of a combined golf divot repair tool, ball marker, cleat tightener dirt scraper and club holder showing our new design;

FIG. 2 is a top plan view thereof;

FIG. 3 is a left side elevational view thereof;

FIG. 4 is a bottom plan view thereof;

FIG. 5 is a right side elevational view thereof;

FIG. 6 is a front elevational view thereof; and,

FIG. 7 is a back elevational view thereof.
